US0D1086394S

(12) **United States Design Patent** (10) **Patent No.:** **US D1,086,394 S**
(45) **Date of Patent:** **** Jul. 29, 2025**

(54) **FAUCET**

(71) Applicant: **XIAMEN LOTA INTERNATIONAL CO., LTD.**, Xiamen (CN)

(72) Inventors: **Huakun Gao**, Xiamen (CN); **Jiaqun Lin**, Xiamen (CN); **Fahong Chen**, Xiamen (CN); **Yunlong Xie**, Xiamen (CN); **Liming Ye**, Xiamen (CN)

(73) Assignee: **XIAMEN LOTA INTERNATIONAL CO., LTD.**, Xiamen (CN)

(**) Term: **15 Years**

(21) Appl. No.: **29/920,961**

(22) Filed: **Dec. 14, 2023**

(30) **Foreign Application Priority Data**

Oct. 27, 2023 (CN) 202330698491.1

(51) LOC (15) Cl. 23-01

(52) U.S. Cl.

(57) **CLAIM**

The ornamental design for a faucet as shown and described.

DESCRIPTION

FIG. 1 is a perspective view of a faucet showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 2;

FIG. 10 is an enlarged view of portion 10 shown in FIG. 3; and,

FIG. 11 is an enlarged view of portion 11 shown in FIG. 5.

The dash-dash broken lines in the drawings depict portions of the faucet that form no part of the claimed design. The dot-dash broken lines represent boundaries of the enlarged portions and form no part of the claimed design.

1 Claim, 11 Drawing Sheets
